HERMETICALLY SEALED JOINT

Hugh B. Johnson, Falls Church, Va., and Le Roy
L. Werner, Washington, D. C.

Application October 26, 1944, Serial No. 560,518

3 Claims. (Cl. 217—65)

(Granted under the act of March 3, 1883, as
amended April 30, 1928; 370 O. G. 757)

1

The invention described herein, if patented may be manufactured and used by or for the Government for governmental purposes, without the payment to us of any royalty thereon.

Generically, the present invention relates to a sealing device for hermetically sealing chambers, and more particularly to a portable and readily dismountable gas tight chamber to be used in connection with military activities. While the ensuing description is directed primarily to a chamber for the fumigation of military equipage, it is of course to be understood that it is of a more comprehensive scope.

We are well aware that the broad concept of providing a gas tight chamber for these purposes is not novel. The prior devices employed to accomplish the desired results are not well adapted for use with highly mobile troops in the field. The fumigating chambers now in vogue are used principally at fixed installations and, as a consequence, are of a more or less permanent nature, thus rendering them inadequate for present military purposes. These devices of necessity must be rather bulky in construction and in addition, due to the somewhat complex structural features, require skilled personnel in their assembly and disassembly.

An important object of the present invention is to overcome the disadvantages now inherent in the art.

A further object is to provide a gas tight chamber for fumigating purposes wherein all juncture points are sealed when the chamber is in its assembled position.

Yet, another object of this position is to provide a mobile gas tight chamber which may be easily and readily assembled or disassembled.

A further object is to provide a gas tight joint which is simple in construction and operation and which employs a minimum of strategic materials in its fabrication.

An additional object is to provide a chamber with means to join two or more structural elements in a hermetically sealed relationship.

The above and other advantageous objects which will hereinafter become more fully apparent are accomplished by the construction and arrangement of the various parts to be described and shown in the attached drawing in which similar reference characters designate the same or similar parts:

Figure 1 is a composite view in perspective of the exterior, showing the method of joining the front and one side panel to the base panel.

Figure 2 is a view in perspective of the interior

2

of the chamber showing the method of joining the front and one side panel to the base panel.

Figure 3 is a fragmental transverse sectional view taken through the chamber showing the manner in which any vertical panel is attached to the base panel.

Figure 4 is a sectional view taken along the line 4—4 of Figure 3 looking in the direction of the arrows.

Figure 5 is a transverse sectional view of another form of stiffener for the locking bolt.

Referring to the drawings and more especially Figure 1, there is shown a base or floor panel 1 made of light weight, gas proof material such as plywood. Front panel 2 and side panel 3 made of the same material as the base 1 are adapted to form the walls of the chamber. For the purpose of simplicity, we have merely shown three of the panel elements, it being understood that 15 the other side panel and the rear panel are made and assembled in the same way as the panels 2 and 3 and that the roof panel is similar to the base panel 1.

An upstanding angle iron rib 5 is secured to the 25 upper face of the floor panel 1 by means of screws or the like 4. It will be noted in Figure 3 that the vertical portion of the angle is longitudinally offset, as indicated at 6, and terminates in a second vertical portion 7, the function of 30 which will later be more fully set forth. A series of spaced bolt assemblies designated generally 8 are provided at predetermined intervals along the angle iron 5 in spaced relation from offset portion 6. These bolt assemblies serve as a part of the 35 locking means whereby the panel members are secured to the base panel 1. A similar upstanding and longitudinally offset angle iron rib 5a is positioned along the vertical edge of the side panel where it is joined to the front panel to 40 provide an effective seal along this point of juncture. As perhaps best illustrated in Figure 3, each bolt assembly comprises a head 9, shank 10, cone nut 11, and a collar 12, which latter element prevents the nut from being removed from 45 the shank. To strengthen and add rigidity to the bolt assembly, a web or stiffener 13 is integrally formed with the angle iron 5. The upper end of the web is enlarged as shown at 14 and is formed with a threaded bore 15 into which the shank of 50 the bolt is adapted to be screwed.

In Figure 5, there is illustrated a modified type of stiffener, and it will be noted that the web 13' is welded along its upper edge to the shank 10, as shown at 14' and along the lower edge to the 55 angle 5 as at 15'.

The horizontal edges of the side panel are provided with slots 16 having an enlarged aperture 17 at the upper end thereof. In view of the fact that the slot 16 cooperates with the bolt assembly 8 to lock or secure the panels to the base panel, there is a slot for each bolt assembly. With reference to Figure 3, attention is invited to the fact that the enlarged aperture 17 of the slot is formed with tapered walls 18 having the same degree of taper as the cone nut 11. This arrangement is efficacious in that it permits a very snug fit between the panel and the angle 5 when the nut 11 is drawn up on the bolt. The horizontal and the vertical edges of the front panel 2 are also formed with a plurality of slots 16a. In Figure 1, it will be noted that the slots in the vertical edge of front panel are cut at an angle with respect to the edge of the panel, thereby enabling the bolt assemblies to be moved into the slots with a minimum of effort.

A groove or recess 19, of dove tail configuration, coextensive with the offset portion 6 of rib 5 is formed in the interior of the side panel element, adjacent both the upper and lower edge thereof. A rubber gasket 20 or similar resilient packing material is imbedded in the groove and the outer exposed surface is substantially flush with the inner surface of the panel element. As will later become more fully apparent, the gasket 20 in conjunction with the vertical portion 7 of the angle iron 5 will effect a gas tight seal between the panel and the base. A similar groove and gasket combination 19a and 20a, coextensive with the offset portion of rib 5a, is provided on the interior of the front panel, extending along the vertical and horizontal edges, to afford a similar seal.

Affixed to the outer face of the side panel, adjacent to the groove 19 is a metal stiffening strip 21 of angle shape. This strip is formed with a plurality of slots 22 having the same dimensions as the slots 16 in the panel element. This member is desirable in that it acts as a washer surface against which the cone nut bears, preventing enlargement of the wood slot, and acting also as a strengthening element for the panel, imparting rigidity to the chamber along its juncture points. A similar stiffening strip 21a is bolted to the horizontal and vertical edges of the front panel, adjacent to the gasket 20a, the function being the same as the stiffening strip 21, previously described.

To set up the apparatus, the front panel 2 is dropped into place on the base panel 1 so that recess 19 and resilient gasket 20 face the offset portion 6 on rib 5 and the slots 16a will register with the bolt assemblies 8. The shock imparted to each bolt assembly will be absorbed by the web 13 and as a result, bending or shearing of the bolt is minimized materially. The nut 11 is then drawn up on each bolt and the vertical portion 7 of the angle 5 is moved into snug engagement with the gasket 20a to effectuate a gas tight seal between the panel and the base panel 1. The side panel 3 is then moved into engagement with the base 1 in such a way that recess 19a and resilient gasket 20a face the offset portion on rib 5a and the slots 16 and the bolts 8 interfit. The panel is dropped at an angle with respect to the front panel to enable the bolt assemblies 8 along the vertical edge to register with the slots 16a in the front panel. When the panel is in position, the nuts are manipulated to hold the side panel in fixed relation to the base and the front panel. The remaining side panels and roof are assembled.

in substantially the same manner. Obviously, by reversing the above procedure, the chamber may be disassembled.

By virtue of the above description, it will be appreciated that we have devised a gas tight chamber which is well adapted for fumigation purposes in the field. The unit may be easily and readily assembled in a minimum of time and without the employment of highly skilled personnel. Moreover, there are relatively few essential working parts and in case of damage or loss, the parts can be easily replaced. In addition, effective gas tight joints are provided which reduce materially the danger of toxic effects of the fumigants used.

It will be fully understood that the foregoing description and accompanying drawings cover only the general and preferred embodiment of the invention and that various changes in construction, proportion, and arrangement of the elements may be made by those skilled in the art, without departing from the spirit and scope of the invention as set forth in the appended claims.

Having thus described our invention, what we claim as new and useful is:

25. 1. A hermetically sealed joint comprising a base member, an upstanding rib mounted on said base member, said rib having a longitudinally extending offset portion, a side member mounted on said base adjacent said rib and provided with a longitudinally extending recess coextensive with and facing said offset portion, a resilient member within said recess, and means spaced from said resilient member and extending transversely through said rib and side member for clamping said offset portion in engagement with said resilient member.

2. A hermetically sealed chamber comprising a base member and a plurality of panel members mounted on said base member, one of said panel members being provided with an upstanding rib, said rib having a longitudinally extending offset portion, and another of said panel members being provided with a longitudinally extending recess coextensive with and facing said offset portion, a resilient member within said recess, and means spaced from said resilient member and extending transversely through said rib and said second panel member for clamping said offset portion in engagement with said resilient member.

3. A hermetically sealed chamber comprising a base member, a horizontal upstanding rib mounted on said base member, said rib having a longitudinally extending offset portion, a plurality of panel members mounted on said base adjacent said rib, each of said panel members being provided adjacent one of its horizontal edges with a longitudinally extending horizontal recess coextensive with and facing said offset portion, a resilient member within said recess, and means spaced from said resilient member and extending transversely through said rib and side member for clamping said offset portion in engagement with said resilient member; one of said panel members being further provided with a vertical longitudinally extending recess adjacent one of its vertical edges and another of said panel members being provided with a vertical upstanding rib adjacent one of its vertical edges, said vertical rib having a longitudinally extending offset portion coextensive with and facing said vertical recess, a vertical resilient member within said vertical recess, and means spaced from said vertical resilient member and extending transversely through said vertical rib and through said

70. 75. 75. 75.

5

vertically recessed panel member for clamping said vertical offset portion in engagement with said vertical resilient member.

Certificate of Correction

Patent No. 2,448,031.

August 31, 1948.

HUGH B. JOHNSON ET AL.

It is hereby certified that error appears in the printed specification of the above numbered patent requiring correction as follows: Column 1, line 35, for the word "position" read *invention*; and that the said Letters Patent should be read with this correction therein that the same may conform to the record of the case in the Patent Office.

Signed and sealed this 16th day of November, A. D. 1948.
